UNITED STATES PATENT OFFICE.

JOSEPH W. TAGGART, OF WATERTOWN, NEW YORK.

PAPER-BAG-BOTTOMING MACHINE.

Application filed November 4, 1921. Serial No. 512,783.

To all whom it may concern:

Be it known that I, JOSEPH W. TAGGART, a citizen of the United States, residing at Watertown, in the county of Jefferson and 5 State of New York, have invented certain new and useful Improvements in Paper-Bag-Bottoming Machines, of which the following is a specification.

This invention relates to a machine for 10 forming and pasting the ends of paper bags, and has for its object to provide novel and simple means for carrying out this work. A particular object is to provide novel, simple and positive mechanism for folding the flaps 15 of the bottom ends of the bags after the same have been pasted, the said folder consisting mainly of a rocking member, which is actuated by certain of the bag-feeding parts, by which the proper timing of the member 20 is effected, and a novel and peculiar cam-guide which effects the rapid and positive folding of one of the end flaps.

The various features and parts of the invention will be understood from the detailed 25 description which follows and by reference to the accompanying drawings, in which—

Figure 1 is the front side elevation of the machine to which my improvement is applied; certain nonessential parts being omitted. Fig. 2 is a diagrammatic view of the cam-guide; showing the different positions of the rocking member during the flap-folding operations. Fig. 3 is a view of the tube 30 from which the bag is made; showing the bottom end slitted preparatory to being folded. Fig. 4 is a view showing the partial folding of the bottom-end of the bag. Fig. 35 5 is a rear-end view of the machine; showing the flap-folding mechanism in various 40 positions; also showing the progress of the bag through the machine. Fig. 6 is a fragmentary view; showing the final operation of the flap-folding parts. Fig. 7 is a sectional view of the eccentric which operates 45 the rocking member. Fig. 8 is a sectional view of the adjustable lever which actuates the rocking flap-folder. And Fig. 9 is a view of the bag after the pasted end-flaps have been folded.

50 In the drawings, 2 and 2' represent the spaced, preferably annular, frame portions which are mounted vertically upon legs 2^a. These sections of the frame are each braced by similar radial arms 2^b, which converge 55 at the center of the said members, and are bored out axially to provide bearings for the

opposite ends of a shaft 3' that supports the main cylinder or drum 3, which receives and carries the bags 4 from the time they are slitted by a pair of rolls 5—5', until the 60 folding and pasting of the bottom ends of the bags are completed and delivered to the usual feed and press rolls 6 and 7—7'. 8 represents the operator's table, upon which the plain tubes 4 are stacked, and from 65 which the tubes are fed singly, as indicated by the dotted line 4, in Fig. 1. The tubes 4 first pass between a pair of feed rolls 8', which direct the tubes toward the slitter rolls 5—5'. After leaving the slitter the 70 tube 4 is carried downwardly bottom end foremost between the roll 5 and the drum 3. Upon reaching the point indicated by the arrow 4^x, the bottom end of the bag is partially folded, as shown in Fig. 4, by a well-known mechanism, which is not shown. When the bottom-end of the bag progresses to the arrow 4^y, paste is applied to the flaps 4' and 4^a by another mechanism (not shown).

The bag 4 is then carried a short distance 80 and encounters a device 9, which creases the bottom near the base of the flap 4', as shown at 4^b in Fig. 4. This creasing is necessary to facilitate the folding of the flap inwardly upon the central or diamond shaped portion 85 4^c of the bag. The foregoing operations are common to bag-ending machines, and the mechanisms for carrying out this preliminary work have not been shown in detail.

The further rotation of the drum 3 (in 90 the direction of the arrows shown thereon), from the creaser 9, carries the partially folded bag, shown in Fig. 4, around to the left-hand side of the drum 3 until it reaches the position shown by dotted lines in Fig. 1, 95 and by the full lines in Fig. 5, wherein the flap 4' points downwardly tangentially, as shown in Figs. 1 and 6, while the flap 4^a is positioned slightly above the horizontal center of the drum and points tangentially in 100 the opposite direction, as shown by the full lines in Fig. 1 and by the dotted lines in Fig. 6, where a device 9' creases the bottom at line 4^d (Fig. 4). The folding of the flaps 4' and 4^a is effected while the bag is being 105 carried from the last described position to the feed rolls 6, by a novel mechanism which will now be described in detail:

The press roll 7, is mounted upon a shaft 7^a, the latter being supported by upright 110 bearing brackets 7^b and 7^c, which are mounted respectively on the annular frame sec-

tions 2—2'. The bracket 7^a is provided with a hollow boss 7^a, into which one end of the shaft 7^a protrudes, and upon this end of the shaft 7^a is rigidly mounted a disc 7^e, which is provided with an eccentric pin 7^f, as shown in Figs. 1, 5 and 7. 10 represents a rocking lever, which is pivoted by a pin 10' to a lateral projection 7^x of the boss 7^a. The lever 10 has a longitudinal groove 10^x facing the disc, in which the pin 7^f is disposed and plays, for rocking the free end of the lever 10 in a vertical plane, as shown by the full and dotted lines in Figs. 1, 5 and 7, by the rotation of the disc 7^e. The under- 15 side of the free end of the lever 10 is provided with a forked perforated lug 10^b, in which is pivoted the upper end of a link 11, the bottom end of the said link being pivoted in the forked free end of an adjustable 20 rocking lever 12, by pins 11'. The lever 12 is slotted at 12' for adjustably receiving the reduced end of a shaft 13, which is supported by bearings 13' mounted rigidly on the frame sections 2—2'. On this end of the shaft 25 13, is rigidly mounted a sleeve 13^a, which is slotted diametrically to slidably receive the lever 12, the said lever being held in place in the said slot by means of a washer 13^b, and a nut 13^c. By this construction and ar- 30 rangement the rotation of the disc 7^e effects the simultaneous vertical rocking of the levers 10 and 12, as shown by the full and dotted lines in Figs. 1 and 5, and this correspondingly partially rotates the shaft 13. 35 The folding of the flap 4' of the bag is effected directly by the following parts: 14—14' represent forwardly projecting spaced arms, whose outer and heavier ends are rigidly secured to the shaft 13, by clamps 40 14^a. These arms are disposed parallel to each other and their inner reduced ends are tied together by a shaft 14^b, which journals in the said ends. To one end of the shaft 14^b is rigidly fitted a short upright lever 45 14^c, whose free end supports a roller 14^d. The roller 14^d is constantly in engagement with an upright cam-guide 15 of peculiar shape, which is best shown in Figs. 1 and 2. The bottom end of the guide 15 is made 50 rigid to the frame 2 by a bolt 15', while the upper end of the said guide is rigidly supported by an upright arm 16, which is rigidly secured to one of the radial bars 2^b, by a bolt 16'; the connection between the 55 arm 16 and the guide 15 consists of a rod or bolt 16^a. The shaft 14^b carries an upright radial wing or paddle 14^e, which engages the flap 4' of the bag 4 and directly effects the folding of the said flap. The 60 wing 14^e is movable with the shaft 14^b when the latter is partially rotated by the action of the roller 14^d over the irregular track presented by the cam-guide 15. These various movements of the wing 14^e are necessary for the proper folding of the flap 4',

which must be swung in substantially a half circle between the start and the finish of the folding operation, which will now be described: A few seconds in advance of the arrival of the bag 4 at the position shown 70 at the left side of the drum 3 in Figs. 1 and 6, the rocking arms 14—14', and shaft 14^b and related parts, are moved to their lowest operative position, shown by the full lines in Fig. 1, and by the lowermost dotted 75 lines in Figs. 2 and 6, ready to begin the folding. This positions the roller 14^d near the bottom of the large bend 15^a of the cam-guide, slightly below the flap 4'. As the drum 3 continues to rotate, the free ends of the arms 14 are tilted upwardly at a slightly faster rate of speed owing to the difference in the length of the levers 10 and 12, and by the time said arms reach the first dotted 80 position or line *a*, (see Figs. 1 and 2), the roller 85 14^d is moved into the deepest portion of the bend 15^a, and this swings the free end of the wing 14^e upwardly and towards the right of the depending flap 4'. The next 90 upward movement of the arms 14 to the position *b* drives the roller 14^d around the abrupt bend 15^b of the cam-guide. This rocks the shaft 14^b in the opposite direction and tilts the wing 14^e leftwards into engagement with the under side of the flap 4' and 95 swings the said flap outwardly substantially to the horizontal position (see Fig. 1). The wing 14^e and flap 4' continue in the last described relation while the arms 14 are swung to the dotted position *c*. In 100 the meantime the roller 14^d travels over the plane surface 15^c of the cam-guide and partially rounds the upper abrupt curve 15^d of the guide. This again carries the said roller slightly to the right and correspondingly 105 rocks the shaft 14^b and the wing 14^e towards the right. The flap 4' then inclines in the opposite direction, towards the drum, and begins its final folding movement, and when the arms 14 are being moved to their highest position, the roller 14^d is moved still further towards the right and rides on the upper plane surface of the guide. During 110 this final upward movement of the rocking members 14, the wing 14^e is swung farther and farther towards the right by the receding of the free ends of said arms which rotate on the axis 13 until the wing 14^e forces the flap 4' tightly against the diamond shaped bottom portion 4^e of the bag to 115 which it adheres. At almost the same instant, the flap 4^a, having progressed to the same extent, comes into contact with a stationary guard 17 and is folded downwardly in the opposite direction upon the flap 4'. This completes the folding of the several bottom end-portions, as shown in Fig. 9. The guard 17 is rigid on a rod 17' which is supported by a bracket 17^a as best seen 120 in Figs. 1 and 6. At the end of the folding 125 130

operation just described, the bag 4 passes between the feed rolls 6, and thence through the press rolls 7-7', by which it is discharged from the machine, as shown by the dotted line 4, at the left in Fig. 1. The several bends of the cam-guide are fashioned and spaced and the timing of the parts 10-12-14-and 14^e are so arranged as to positively fold the flap 4' a fraction of a second in advance of the final folding of the overlaying flap 4^a. 14^f represents a tension spring which connects with the arm 14 and with the bottom-end of the lever 14^e. This spring exerts its tension for resiliency holding the roller 14^d in constant engagement with the cam-guide 15. The bags 4 travel through the machine at a very rapid gait and as the bags are made to hug closely the face of the drum 3, which rotates on a different axis than the arms 14-14', the said arms must be operated in faster time, in order that the wing 14^e may perform its variable movements, as described. When properly constructed and adjusted my flap folding mechanism operates continuously for long intervals without failure and enables me to operate the bag-ending machines at higher speed and with greater accuracy and economy than any of the older machines of the class known to me.

The shaft 7^a carries a gear 18 which is driven by a gear 19 (see dotted lines in Fig. 1) the latter being mounted on a shaft 19', to one end of which is fitted a pulley 19^a which is driven by a belt 19^b. The opposite end of shaft 19' is fitted with a hand-wheel 19^c, by which the various parts of the machine may be rotated manually. The gear 18 drives a similar gear 18' mounted on a shaft 18^a which carries the rolls 7'. The lowermost feed roll 6 preferably drives the drum 3 by a suitable gearing (not shown.)

Having thus described my invention, what I claim is—

1. In a device for folding the end flaps of paper bags, the combination with the drum which carries the bags through an

ending machine, and the power driven press rolls which receive the bags from the drum, of a disc mounted on the shaft of one of said press rolls, said disc having an eccentric pin, a pair of levers rocked by said pin, a pair of arms adapted to be rocked by said levers, a rockable wing carried by said arms, a cam-guide disposed vertically near said drum, and means operatively connecting said wing with said cam-guide whereby variable lateral movements are imparted to said wing by the vertical movements of said arms for folding one of the bottom-end flaps of each bag as it is carried around by said drum.

2. In a flap folder for paper bags, the combination with the drum which carries the bags during the bottoming operations, and a driven press roll which receives the bags from said drum, of an eccentric device carried by the shaft of said press roll, rocking levers actuated by said eccentric, a flap-folding member adapted to be moved in opposite directions in a vertical plane, said member having a wing which successively engages the bottom-end flaps of the bags as they are carried around by said drum, and a vertically disposed cam-guide having an irregular face adapted to impart variable lateral movements to said wing for effecting the folding of one of said flaps.

3. In a flap folder the combination with a drum which carries the paper bag during the bottoming operations, of a vertically rocking member, a wing pivotably supported by said member adapted to engage one of the bottom-end flaps of the bag and to fold said flap against the adjacent portion of the bag, a vertical guide for effecting variable movements of said wing during the folding periods, an eccentric device for operating said member, and a slotted lever interposed between the eccentric device and said member for varying the length of the strokes of said member.

In testimony whereof I affix my signature.

JOSEPH W. TAGGART.
